SNAGGING WHEEL

Frank Wahl, North Bergen, N.J., assignor to Western Electric Company, Incorporated, New York, N.Y., a corporation of New York

Application November 27, 1957, Serial No. 699,358

10 Claims. (Cl. 242—25)

This invention relates to continuous strand takeup units and particularly to snagging wheels for such units.

In the processing of various types of strands, such as the extrusion of plastic on wires, the operation is continuous and it is necessary to provide a continuous takeup therefor. During operation of conventional continuous takeup units the strand is wound upon one takeup reel until that reel is filled or until a predetermined length of the strand has been wound thereon, after which the distributor, acting to distribute the strand, is shifted laterally away from the area of the filled reel and into the area of another or empty reel where it will distribute the strand on the other reel. Each reel is provided with a snagging wheel adjacent its inner head to snag the portion of the strand passing from one reel to the other, to move the strand portion relative to a stationary cutter where it is cut, and to hold the cut ends thereby preventing the strand from unwinding from the full reel and holding the new leading end for winding the strand on the empty reel. In the past, the hooks of the snagging wheels have been fixedly mounted, presenting various problems including the problem of readily removing the ends of the strands from the hooks, the location of the hooks for strands of various sizes and the mounting of the hooks so that the strand engaging surfaces will be like distances from the periphery of the wheel.

The object of the present invention is a snagging wheel for a continuous takeup unit which embodies a solution to these problems.

In accordance with the object of the invention the snagging wheel includes a circular body adapted for mounting on a drive for a takeup reel and including like hook members having leg portions extending through spaced apertures in the periphery of the body member and connected to means movable to free the hooks for outward movement to release a hooked strand portion and movable into like strand engaging positions.

More specifically, the hooks are normally urged outwardly by individual springs but are controlled in their positions by adjustable screws with conical ends carried by an annular member normally urged outwardly by springs but movable inwardly, during mounting of a reel in position, to force the conical ends of the screws into tapered apertures, disposed in the leg portions of their respective hooks, to draw the hooks inwardly toward the center or axis of the wheel to position the hooks for firmly gripping or snagging the strand when transferred from one takeup reel to another.

Other objects and advantages will be apparent from the following detailed description when considered in conjunction with the accompanying drawings, wherein:

Fig. 1 is a front elevational view of a left snagging wheel;

Fig. 2 is an enlarged sectional view taken along the line 2—2 of Fig. 1 with the snagging wheel mounted in the takeup unit;

Fig. 3 is a fragmentary front elevational view of a right snagging wheel, and

2

Fig. 4 is a top plan view of a continuous takeup mechanism embodying the invention.

The snagging wheels shown in Figs. 1 and 3 are identical in every detail with the exception of the positions of the hooks to condition them for right and left hand takeup reels. For this reason the description will be directed mainly to the snagging wheel 10 shown in Fig. 1 rather than the snagging wheel 11 shown in Fig. 3. The wheel 10 has a circular body 12 centrally apertured at 14 for mounting on a cone center 15 of a pulley portion 16 of a drive unit. The body 12 has a pin 17 fixedly mounted therein with one end positioned to enter the conventional aperture in one end or head of a takeup reel 18 and the other end entering an aperture 19 of the member 16 for connecting the body 12 to the member. Screws 20 complete the connection of the body 12 to the member 16. The screws 20 extend through an enlarged annular portion 21, which serves as a bearing for an annular element 22. The annular element 22 is held against displacement by a retaining ring 25 having an inwardly projecting lip 26 cooperating with an outwardly projecting lip 27 of the element 22 to limit axial movement of the element. A plurality of springs 28 housed in pockets 29 disposed at spaced positions about the element 22 engage the adjacent surface of the body 12 to uniformly urge the element to the left of Fig. 2 until the lips 26 and 27 meet. An annular flange 30 integral with the element 22 extends to the left a distance sufficient to engage the head of the reel 18.

The body 22 has an annular peripheral flange 32 with a tapered surface 33 and radially spaced apertures 34 to receive like hooks 35. The hooks 35 are substantially L-shaped with their longer leg portions 37 extending through the apertures 34 and provided with apertures 36 near their inner ends. The shorter leg portions of the hooks 35 are identified as jaw portions 38. The apertures 36 taper outwardly from their cross sectional center lines to provide a pair of tapered surfaces in each aperture to cooperate with a conical end of a screw 41.

Apertures 40 in the jaw 12 are aligned with the screws 41 to allow longitudinal movement of the screws. The screw 41 is mounted in a threaded aperture in the element 22 at each hook position where the element is recessed at 42 to receive each hook. The annular member 25 is recessed in each instance at 43. Each screw 41 is

provided with a lock nut 44 whereby it may be adjusted to locate its respective hook at a desired position relative to the periphery of the wheel when in the operated position shown in Fig. 2. To initially set the screws 41 a desired number of screws 46 may be used, extending them through apertures 47 in the body 12 and into threaded apertures 48 of the element 22. Through the aid of the screws 46 the element 22 is forced in its operated position and held until all of the hook actuating members or screws 41 are

adjusted and locked by their lock nuts 44 to assure location of the hooks 35 into the desired position when a takeup reel 18 is mounted in place. After the adjustments have been made the screws 46 may be removed, allowing the springs 28 to function. When the element 22 is moved outwardly by the springs 28 during removal of a reel 18 individual springs 50, mounted on the inner portion of the flange 32 and having their free ends disposed in notches 51 of the hooks, cause outward movement of the hooks when released. The outer legs of the hooks 35 have tapered surfaces 52 to assure engagement

with the strand and also tapered surfaces 53 to force the strand into any one of the tapered recesses formed by the surface 53 and the periphery of the flange 32 to produce a firmly gripped strand portion. The only difference between the wheel 10 of Fig. 1 and the wheel 11 of Fig. 2 is the direction in which the outer portions of the hooks 35 extend. Their positions in Fig. 3 are the reference

of those in Fig. 1 and during the initial assembly of the hooks the springs 50 of Fig. 3 are moved about the axis of the mounting screws 55 to engage the notch 51 of its hook 35.

The structure shown in Fig. 4 is a continuous takeup mechanism showing the two snagging wheels 10 and 11. In the present illustration the takeup reel 18 shown mounted on the drive member 16, has been forced by a rotatable cone center 60 against the fixed position cone center 15. In the present illustration the cone center 60 is moved axially by a piston (not shown) of an air cylinder 61. In a similar manner a drive member 16' for a takeup reel 18' has a fixed position cone center 15' cooperating with a movable cone center 60' moved axially by a piston (not shown) of an air cylinder 61'. The drive members 16 and 16' are operatively connected through belts 62 and 62' to shafts 63 and 63', these shafts being connected through belts 64 and 64' to members 65 and 65'. The members 65 and 65' normally are free to ride on a shaft 67 of a suitable drive means such as a motor 68. The shaft 67 extends through the entire structure shown at the top of Fig. 4 and has fixed clutch members 69 and 69' mounted thereon. The members 65 and 65' have clutch members 70 and 70' adapted for selective connection with their respective clutch members 69 and 69'. The members 65 and 65' also carry braking elements 71 and 71' positioned away from a fixed brake member 72 when their respective clutch members 69—70 or 69'—70' are engaged but to engage the fixed brake member 72 when the clutch members are released or disengaged. In the present illustration reel 18 is being filled with a strand 74 extending around a sleeve 75 and through the forked end of a distributor arm 76 movable in the conventional manner by a reversible threaded shaft 77. When the reel 18 is filled the distributor arm 76 will be moved laterally through axial movement of the shaft 77 to transfer the strand 74 to the takeup reel 18'. It is conventional practice to start rotation of the takeup reel 18' prior to the transferring operation so that the snagging wheel 11 will be rotating at the same speed as a snagging wheel 10 when the strand is transferred from the full reel to the empty reel. A stationary knife or cutter 78 positioned between the snagging wheels 10 and 11 serves to cut the strand between the wheels, leaving the ends secured to the hooks which have snagged the strand portion between the reels.

During operation of the mechanism shown in Fig. 4 it will be apparent that, when the reel 18 is filled or a predetermined measured length of the strand has been wound thereon and the distributor arm 76 is shifted from the solid line position to the dotted line position, the portion of the strand 74 extending over the peripheries of the wheels 10 and 11 will be snagged by the next adjacent hooks. This laterally moved portion of the strand is tentatively stationary so that the approaching pair of hooks of the snagging wheels 10 and 11 will firmly snag and hold the ends of this portion so that it may be severed. Furthermore, the severed ends of the strand will be firmly held by the hooks which have gripped the strand to hold the strand on the full reel against unwinding until that reel is stopped and action is taken by the removal of the cone center 60 to allow the filled reel to be removed. No action is necessary on the part of the operator to remove the end of the strand from the hook 35 of the snagging wheel 10 due to the fact that the moment the holding force for the takeup reel 18 is removed by movement of the cone center 60 to the left, the springs 28 will function to move the elements 22 outwardly, moving the conical ends 40 of the screws 41 outwardly a distance, not sufficient to completely remove their connections with their hooks 35 but a distance sufficient to allow each hook 35 to be moved outwardly by its spring 50 to automatically free the end of the strand, allowing the operator to concentrate his full effort on the reel itself. There is another feature

which has not been brought out regarding the takeup reel 18 but will be apparent from following the action of the takeup reel 18'. The starting end of the strand is held by one of the hooks 35 of wheel 11 and after the takeup reel 18' is filled and the transfer arm 76 is returned to the solid line position, where a new empty reel 18 is mounted between the centers 15 and 60, another portion or the trailing end of the strand wound on the reel 18' will be snagged by another hook of wheel 11. This makes it doubly important that the ends of the strands held by the hooks be freed upon removal of the force holding the reels in place. If the snagging hooks were not free to move outwardly and caused to move outwardly by the springs 50, the operator would have to remove the strands from the hooks and in many instances if the strands become so firmly wedged in place that easy removal of the strands would not be possible, they may become broken and remain in the hooks, eventually filling the areas and rendering the hooks ineffective.

Equally important, with the freedom of the hooks to move outwardly to free the strand portions, is the assurance of the hooks returning to their predetermined operated positions prior to receiving the next strand portion. This is made possible through the accurate setting of the screws 41 with their conical ends 40 in either portion of the aperture 36 in its respective hook 35. In other words, the hooks 35 are caused to lie against the inner wall of the body 12 and the element 22 is forced, by the reel being moved into the mounting position on the cone center, against the springs 28 until the element engages the inner surface of the body so that each screw 41, having been adjusted in this closed position through the assistance of the screws 46, will assure accurate positioning of its hook in returning to the snagging position.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. A snagging wheel for a continuous takeup unit wherein axially aligned drive means for takeup reels are selectively driven to rotate the takeup reels to take up a continuous strand on one reel until that reel is filled and transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, hooks having leg portions extending through the apertures in the flange and jaw portions extending like distances in the direction of rotation of the one driving means and having tapered surfaces cooperating with the adjacent portions of the flange to snag and firmly hold a portion of the strand when moved from a filled reel across the flange, and means rendered effective to move the hooks outwardly on removal of the filled reel to free the strand portion.

2. A snagging wheel for a continuous takeup unit wherein axially aligned drive means for takeup reels are selectively driven to rotate the takeup reels to take up a continuous strand on one reel until that reel is filled and transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, and hooks having leg portions extending through the apertures in the flange and jaw portions extending like distances in the direction of rotation of the one driving means and having tapered surfaces cooperating with the

adjacent portions of the flange to snag and firmly hold a portion of the strand when moved from a filled reel across the flange, the hooks being free to move outwardly from their snagging positions to free the snagged wire portion when the filled reel is removed from the unit.

3. A snagging wheel for a continuous takeup unit wherein axially aligned drive means for takeup reels are selectively driven to rotate the takeup reels to take up a continuous strand on one reel until that reel is filled and transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, hooks having leg portions extending through the apertures in the flange and jaw portions extending like distances in the direction of rotation of the one driving means and having tapered surfaces cooperating with the adjacent portions of the flange to snag and firmly hold a portion of the strand when moved from a filled reel across the flange, the hooks being free to move outwardly from their snagging positions to free the snagged wire portion when the filled reel is removed from the unit, and means responsive to an empty reel being forced into operative connection with its drive means to return the hooks to their snagging positions.

4. A snagging wheel for a continuous takeup unit wherein axially aligned drive means for takeup reels are selectively driven to rotate the takeup reels to take up a continuous strand on one reel until that reel is filled and transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, hooks having leg portions extending through the apertures in the flange and jaw portions extending like distances in the direction of rotation of the one driving means and having tapered surfaces cooperating with the adjacent portions of the flange to snag and firmly hold a portion of the strand when moved from a filled reel across the flange, and means rendered effective to move the hooks outwardly on removal of the filled reel to free the strand portion, means responsive to an empty reel being forced into operative connection with its drive means to return the hooks to their snagging positions.

5. A snagging wheel for a continuous takeup unit wherein axially aligned drive means for takeup reels are selectively driven to rotate the takeup reels to take up a continuous strand on one reel until that reel is filled and transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, hooks having leg portions extending through the apertures in the flange and jaw portions extending like distances in the direction of rotation of the one driving means and having tapered surfaces cooperating with the adjacent portions of the flange to snag and firmly hold a portion of the strand when moved from a filled reel across the flange, an annular element supported by the body and movable from a normal position spaced from the body to an operated position adjacent the body by a takeup reel forced into operative connection with the drive means, and locating members carried by the element to engage the leg portions of the hooks to move them into their snagging positions.

6. A snagging wheel for a continuous takeup unit wherein axially aligned drive means for takeup reels are selectively driven to rotate the takeup reels to take up a continuous strand on one reel until that reel is filled and

transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, hooks having leg portions extending through the apertures in the flange and jaw portions extending like distances in the direction of rotation of the one driving means and having tapered surfaces cooperating with the adjacent portions of the flange to snag and firmly hold a portion of the strand when moved from a filled reel across the flange, an annular element supported by the body and movable from a normal position spaced from the body to an operated position adjacent the body by a takeup reel forced into operative connection with the drive means, locating members carried by the element to engage the leg portions of the hooks to move them into their snagging positions, and means actuatable to adjust the locating members relative to their hooks to adapt the locating members to locate the tapered surfaces of the jaw portions of the hooks at predetermined variable positions relative to the periphery of the flange portions for snagging strands of various sizes.

7. A snagging wheel for a continuous takeup unit wherein axially aligned drive means for takeup reels are selectively driven to rotate the takeup reels to take up a continuous strand on one reel until that reel is filled and transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, hooks having leg portions extending through the apertures in the flange and jaw portions extending like distances in the direction of rotation of the one driving means and having tapered surfaces cooperating with the adjacent portions of the flange to snag and firmly hold a portion of the strand when moved from a filled reel across the flange, an annular element supported by the body and movable from a normal position spaced from the body to an operated position adjacent the body by a takeup reel forced into operative connection with the drive means, locating members carried by the element to engage the leg portions of the hooks to move them into their snagging positions, and means to move the annular element away from the body when a takeup reel is removed to cause the locating members to free their hooks to move outwardly limited distances to free the snagged strand.

8. A snagging wheel for a continuous takeup unit wherein axially aligned drive means for takeup reels are selectively driven to rotate the takeup reels to take up a continuous strand on one reel until that reel is filled and transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, hooks having leg portions extending through the apertures in the flange and jaw portions extending like distances in the direction of rotation of the one driving means and having tapered surfaces cooperating with the adjacent portions of the flange to snag and firmly hold a portion of the strand when moved from a filled reel across the flange, an annular element supported by the body and movable from a normal position spaced from the body to an operated position adjacent the body by a takeup reel forced into operative connection with the drive means, locating members carried by the element to engage the leg portions of the hooks to move them into their snagging positions, means to move the annular

element away from the body when a takeup reel is removed to cause the locating members to free their hooks to move outwardly limited distances to free the snagged strand, and individual means to move the hooks outwardly when freed for such movement.

9. A snagging wheel for a continuous takeup unit wherein axially aligned drive means for takeup reels are selectively driven to rotate the takeup reels to take up a continuous strand on one reel until that reel is filled and transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, hooks having leg portions extending through the apertures in the flange and jaw portions extending like distances in the direction of rotation of the one driving means and having tapered surfaces cooperating with the adjacent portions of the flange to snag and firmly hold a portion of the strand when moved from a filled reel across the flange, an annular element, having spaced threaded apertures therein, supported by the body and movable from a normal position spaced from the body to an operated position adjacent the body by a takeup reel forced into operative connection with the drive means, the leg portions of the hooks having like apertures adjacent their inner ends and with truncated cone shaped surfaces, and locating members threadedly disposed in the spaced apertures of the element and having conical ends movable in their respective apertures of the hooks to free the hooks for outward movement on removal of a takeup reel and to return their hooks to snagging positions when a takeup reel is forced into engagement with its drive means.

10. A snagging wheel for a continuous takeup unit wherein axially aligned drive means for takeup reels are

selectively driven to rotate the takeup reels to take up a continuous strand on one reel until that reel is filled and transfer the strand to the other reel, the unit also including means operable to force the reels for operative connection with their drive means, the snagging wheel comprising a circular body secured coaxially to one of the drive means, rotatable therewith and having an annular peripheral flange with radially spaced apertures therein, hooks having leg portions extending through the apertures in the flange and jaw portions extending like distances in the direction of rotation of the one driving means and having tapered surfaces cooperating with the adjacent portions of the flange to snag and firmly hold a portion of the strand when moved from a filled reel across the flange, an annular element, having spaced threaded apertures therein, supported by the body and movable from a normal position spaced from the body to an operated position adjacent the body by a takeup reel forced into operative connection with the drive means, the leg portions of the hooks having like apertures adjacent their inner ends and with truncated cone shaped surfaces, and locating members threadedly disposed in the spaced apertures of the element and having conical ends movable in their respective apertures of the hooks to free the hooks for outward movement on removal of a takeup reel and to return their hooks to snagging positions when a takeup reel is forced into engagement with its drive means.
